PORTABLE PROJECTING AND SOUND
REPRODUCING APPARATUS

Carl M. Weber, Rochester, N. Y.

Application October 29, 1934, Serial No. 750,541

2 Claims. (Cl. 88—16.2)

This invention relates to portable moving picture projectors including sound reproducing equipment and has for its object to divide the equipment in several easily handled small units for transportation purposes and provide these units with means whereby the units can be quickly and easily brought together and mechanically and electrically connected at the same time with the aid of combined mechanical and electrical connecting members.

This and other objects of this invention will become more readily apparent from the detailed description thereof which follows, reference being had to the accompanying drawings in which Figure 1 is a detail perspective view of the combined amplifier and loudspeaker in portable form.

Figure 2 is a detail perspective view of the combined projector and sound reproducer in portable form.

Figure 3 is a perspective view of the combined projector, sound reproducer with the amplifier mechanically and electrically connected and attached thereto and forming the base therefor.

Figure 4 is a detail top plan view of the amplifier.

Figure 5 is a bottom plan view of the projector.

Figure 6 is an end elevation of the amplifier and projector mounted thereon with portions of the projector broken away.

In the several figures of the drawings like reference numerals indicate like parts.

My present invention is especially adapted for small portable sixteen millimeter film projectors provided with a sound reproducer including an amplifier and a loudspeaker. As illustrated in the figures this equipment, in order to make it readily transportable, is divided so as to provide but two carrying cases illustrated in Figures 1 and 2. The carrying case illustrated in Figure 1 comprises the loudspeaker unit 1 and the amplifying unit 2 which are suitably held together so as to be readily transportable by means of the handle 3.

The carrying case illustrated in Figure 2 contains the projector with the sound reproducing apparatus which are fixedly mounted in the case so as to be readily transportable by means of the handle 5. The mechanism of the projector and sound reproducer is shown in Figure 3 in which one side of the case is swung open for the adjustment thereof. At one end of the outside of the case 4 is provided the clip 6 and at the top of the case is provided a similar clip 7. These 55 clips are adapted to have the brackets 9 and 10

removably mounted thereon for the support of the film reels 11 and 12. The brackets are suitably stored within the case surrounding the loudspeaker 1.

To set up the combined film projecting and sound reproducing equipment, the amplifier section 2 is removed from the loudspeaker section and placed on a suitable support to provide a horizontal base for the projection unit case 4. As illustrated in Figures 3, 4 and 6, the amplifier 10 unit, when used as a base, has an elevated platform 13 which is located intermediate the bank of radio tubes 14 on one side and the control panel 15 on the other side. At one end of the platform 13 is provided the socket 16 for the reception of the plug connection which furnishes the electric power for the complete operation of the projection and sound apparatus and at the opposite end of the platform is provided the socket 17 for the reception of the plug connection from the amplifier unit to the loudspeaker. In this way one electrical extension cord leading to the equipment furnishes the electric current for the complete operation of the equipment and another electrical extension cord leads from the equipment to the loudspeaker to permit its location at the most advantageous point for the audience.

For the mechanical and electrical connection between the amplifier unit and the combined projection and sound unit, the platform of the amplifying unit is provided with three plugs 18, 19 and 20. Each of these plugs comprises an enlarged base with a cylindrical projection which in the plug 20 carries three prongs 21, 22 and 23 and in plugs 18 and 19 carry two prongs 24 and 25.

The plugs are fixedly mounted on the platform and their prongs provide the electrical connection between the socket 16 and the electric motor 26 and projection lamp located in the housing 27 and also between the amplifying mechanism of the amplifying unit and the sound reproducing apparatus of the projector. The three prong plug 20 serves as the electrical connection for the operation of the motor and the projection lamp and the two prong plugs 18 and 19 serve as the electrical connection between the sound reproducing mechanism, the amplifier and the loudspeaker. To complete the electrical connections as above described, the plugs are inserted into the corresponding sockets 28, 29 and 30 carried by the base of the projection apparatus as illustrated in Figures 4 and 5. These sockets are mounted in the base 31 of the projection

apparatus and suitable openings in the case surrounding the apparatus permit the insertion of the plugs into the sockets as illustrated in Figure 6. While the electrical connection is made as above pointed out, the mechanical connection between the amplifier unit and the projection apparatus, which holds the projection apparatus in the proper position on the amplifier unit, is made by the engagement of the plugs of the amplifier unit which also form suitable guide posts into the sockets of the projection apparatus and locks these two units together in their proper relative position with the bank of radio tubes on one side of the projection apparatus and the control panel on the other side thereof where the control members are readily operable on the side of the apparatus which can be opened for adjustment as illustrated in Figure 3.

On the control panel are provided suitable switches 32, 32 to turn on and off the electric current for the various electrical devices of the combined apparatus and the control knobs 33, 33 with which the volume of the sound apparatus is adjusted. A suitable socket 34 is provided for the connection of a microphone or the use of a talking machine to be used in connection with the projection apparatus.

From the foregoing it will be seen that the arrangement and permanent mounting of the various parts of the combined projection and sound equipment in two carrying cases makes it possible to electrically and mechanically connect and to set up the entire mechanism in a minimum time without any chance of making an error in either the mechanical or electrical connection in the set up. The equipment can of course be dismantled at an equally short time and in addition divided and rearranged into two carrying cases for the ready transportation thereof.

40 I claim:

1. A portable talking-motion-picture apparatus adapted to be readily transported by hand in the form of two containers and quickly set up for

operation as a single unit, comprising one container having a plurality of female connecting members and another container having a corresponding number of male connecting members for mechanically connecting and removably supporting said first container in a predetermined position on said second container, said first container enclosing a sound on film projecting mechanism, a film feeding mechanism and a sound reproducing mechanism with electrical connectors for the operation of said mechanism leading to and from said female connecting members, said second container having a removable cover embodying a loud speaker unit located over the male connecting members within the container to cover the male connectors of said second container for carrying purposes and expose the male connectors for the connection and support of the first container on the second container, on the removal of the cover and provide a loud speaker unit that may be mounted remotely from the combined first and second container, said second container also enclosing amplifying means and control means with electrical connectors leading to and from said male connecting members and electrical connecting members within said mechanical connecting members to connect said electrical connectors of said first container with the electrical connectors of said second container and provide the unitary control of said combined film projecting, film feeding, sound reproducing and amplifying mechanisms by the control means of said second container while said first container is supported and mechanically connected to said second container in a predetermined position.

2. A portable talking-motion-picture apparatus as set forth in claim 1 with a single electrical connecting member provided on said second container and electrically connected to said electrical connecting members to provide a single source of electricity for the operation of the mechanism in both of said containers.

CARL M. WEBER.
